UNITED STATES PATENT OFFICE

2,534,258

GUN SIGHT

Daniel V. Gallery, Jr., United States Navy

Application March 31, 1941, Serial No. 386,090

1 Claim. (Cl. 33—49)

(Granted under the act of March 3, 1883, as amended April 30, 1928; 370 O. G. 757)

1

This invention relates to automatically compensating gun sights for flexibly mounted aerial machine guns.

In firing a flexibly mounted, or turret mounted machine gun from a moving aircraft, a certain correction must be applied to the aim of the gun to compensate for the velocity imparted to the projectile as a result of the movement of the aircraft. This correction is known as "gunner deflection." The magnitude of the angle at which the gun barrel is offset from the line of sight to correct for the gunner's deflection is dependent upon the direction in which the gun is pointed relative to the line of flight and upon the air speed of the firing aircraft.

The fundamental principle by which the correction is obtained, which is old in the art, is to effect an offset of one of two sighting members. In my invention I have perfected an automatic means for offsetting the forward sight, the offset being always in the direction of motion of the aircraft. The amount of the offset may be determined by considering a simple parallelogram formed by the sighting members in which the distance between the axis of the forward and rear sighting member is a function of the muzzle velocity of the bullet and its direction is parallel to the axis of the bore of the gun. It, therefore, represents the component of motion of the bullet due to the explosion of the charge in the chamber of the gun. The length of the offset of the forward sight from its axis is proportional to the same function of velocity and represents the air speed of the craft and its direction. It is at all times parallel to the motion of the aircraft, and is therefore the vector component of the motion of the bullet due to the motion of the craft. The line of sight as determined by the center of the two sighting members is the resultant of the two components and represents the direction and velocity of the bullet, due to both forces.

This resultant is the desired sight line to be laid point blank at the target, assuming the target to be stationary and further assuming that the deflection of the bullet from its straight line path due to the force of gravity acting on the bullet is so small that it may be disregarded. In actual practice the sight line is corrected for the speed and direction of the target by means well known to the art; however, corrections for the force of gravity are seldom necessary, since the ranges at which these sights are effective are relatively short and the trajectories are substantially flat.

I am here primarily concerned with the correction for "gunner's deflection," and my invention consists particularly in improvements of the prior art gun sights, especially the gun sights of the type illustrated and described in the U. S.

2

patent to Inglis, 1,650,628, to which a more particular reference will be made later in this specification. I have also devised other means for introducing the correction for "gunner's deflection," which is made the subject of my copending application No. 389,844, filed April 23, 1941.

It is an object of my invention to provide a gun sight having two sighting members, one of which is mounted on a pivoted arm so that the sight may be offset both laterally and longitudinally as the gun is moved in elevation or in train.

It is a further important object of this invention to provide an automatic adjustment for the movable sight member which will maintain the axis of the arm carrying the movable sighting member parallel to the fore and aft axis of the aircraft, irrespective of the angle of elevation or train of the gun relative to the axis.

It is also a further object of this invention to provide a means for easily and quickly adjusting the position of the sighting member relative to its support so that the length of the offset may be adjusted to compensate for changing airspeeds of the aircraft.

It is another object of this invention to provide a gun sight which automatically compensates for "gunner's deflection" in a turret mounted aerial machine gun.

It is an important feature of my invention that the offset of the sighting member always be in a direction of motion of the aircraft through the air, i. e., always parallel to its keel or longitudinal axis, regardless of the position of the gun. The automatically adjusted gun sights of the prior art have failed to accomplish this specific purpose. For example, the corrections introduced by the device illustrated in the patent to Inglis, 1,650,628, are only approximately correct over a limited range of elevations and train, while the corrections introduced by the apparatus which constitutes my invention are correct for any angle of elevation or train. Certain constructional features of my invention which are designed to produce this result are novel, and while they do not appear here as specific objects of my invention, they are important and are made the subject matter of the appended claim.

With the foregoing and other objects in view, the invention consists in the construction, combination and arrangement of parts hereinafter described and illustrated in the drawings, in which:

Fig. 1 is a side elevation of a ball type turret, as used on aircraft, with parts broken away to show my invention as applied to a turret mounted aerial gun.

Fig. 2 is a vertical cross-section looking from the front of the above turret, showing the drive mechanism for the sight.

Fig. 3 is a detail cross-sectional view of the turret training gear and motor, showing also the outline of the fuselage shell.

Fig. 4 is a vertical, longitudinal, sectional view of the front sight.

Fig. 5 is a vertical, cross-sectional view taken on the line 5—5 of Fig. 4.

Fig. 6 is a side elevation of the front sight and shows same applied to a gun with stationary mount, whether upon aircraft, watercraft or land vehicle.

Fig. 7 is a diagrammatic view showing in plan the aiming of a gun equipped with the mechanical front sight, depicting the approach of the target 45° off the port bow.

Fig. 8 is a diagrammatic view showing in plan the aim for a target 30° off the port stern.

Fig. 9 is a diagrammatic view showing in elevation the approach of a target at 45° elevation ahead. In each of the diagrammatic views of Figs. 7, 8, and 9 the target is assumed to be stationary.

Fig. 10 is a front elevational view of a modification of my invention.

Fig. 11 is a side view of the modification illustrated in Fig. 10, and

Fig. 12 is a plan view of the modification as illustrated in Figs. 10 and 11.

Referring now to the drawings, in which Figs. 1, 2 and 3 illustrate my invention as applied to turret mount machine gun. The turret per se, which forms no part of my invention except as modified to incorporate the sight adjusting mechanism, is indicated generally at 10. In Fig. 1 part of the turret structure, including the windows 11 and channel shaped formers or frames 12 are broken away to show the gun mount and sighting mechanism. The fixed machine gun 13 is secured to the turret by means of the supporting brackets 21 and 22. The forward bracket 22 is secured to the channel former or frame 12 and to the forward gun mount adapter 23. The Y bracket 21 is secured to the gun at both the forward and rear adapter 23 and 24 respectively, and to the base of the turret structure at 14.

The turret is supported at the bearing pedestal 25 so as to be rotatable about the lateral or elevational axis through the trunnion 57. The reversible variable speed motor 26, with follow-up reduction gearing indicated at 27 is provided for rotating the turret about the lateral or elevational axis to elevate or depress the gun. The base of the bearing pedestals 25 are supported on an inner ring 28. This inner ring 28 is rotatably supported and spaced from an outer ring 30 by means of the upper and lower rollers 29 and 31. The outer ring 30 is supported by the hull structure of the aircraft.

A reversible variable speed motor 32 is supported on the base structure 19 formed by the inner ring of the turret and carries a pinion 33 at the outer end of its driveshaft. This pinion is in mesh with a ring gear 34 which is secured to the hull supported, outer ring 30, and provides a driving engagement therewith, whereby the turret may be moved about its longitudinal or azimuthal axis to train the gun.

The lever 35, Fig. 2, controls the direction and speed of turret rotation and elevation. Movement of this lever fore and aft results in rotation about the elevational axis, while movement of the lever athwartships results in movement of the turret about the azimuthal axis. The rate of movement of the lever determines the rate of movement of the turret and a diagonal move-

ment of the control lever will result in both an elevational and azimuthal movement of the turret. The motor control mechanism, which is responsive to the movement of the lever, is not disclosed, since it forms no part of this invention.

A suitable ammunition box 16 is carried in the forward part of the turret and the link ammunition is fed to the gun chamber by way of the ammunition chute 15. The chute 17 is provided to receive the ejected cases and links forming the ammunition belt. A suitable gunner's seat is also provided and indicated generally at 18 in the drawing.

The forward adjustable bead sight 40 is secured to the recoil guide and slide 38 by means of the bracket 37. For the rear sight I have selected the common ring sight 38. This rear ring sight is mounted on the rear "gun mount adapter" 24. I have previously used the word "sight" herein as applying to my device as a whole and also as applying to the specific sighting member such as the bead 40, or the ring sight 38. However, since the sighting members could take some form other than that disclosed, I shall hereinafter, for the sake of clarity, refer to the sighting members as the "bead" and "ring" sights, although I do not intend to be so limited.

Referring now to Figs. 4 and 5, which show in enlarged views the structural detail of the bead adjustment. The body 50 of the adjustable bead structure is rotatably supported in a bore 39 of the bracket 37 by means of the laterally extending spindle 52, formed integrally with said body. The bead 40 is secured to a laterally offset arm 41. This arm is rotated about the axis 5—5 of the pivotal stem 45 once for each complete revolution of the turret about its azimuthal axis. The pivotal stem 45 is provided with an enlarged collar portion 46 which has an opening 47 drilled therein to provide an adjustable support for the arm, so that the distance between the center of the bead 40 and the axis of the stem 45 may be adjusted for changing air speeds. A set screw 42 is threaded in the collar 46 so as to engage the arm and hold it in its adjusted position. As illustrated, the pivotal stem 45 is reduced in cross-section over a considerable length at the end opposite the collar. This portion of the shaft is rotatable in the bearing 48 which is held in a cylindrical recess formed in the body portion 50 by means of the set screw 49. The stem 45 is held in the body portion 50 by another set screw 43 which engages the recessed neck 44 of said stem 45. One end of the flexible driveshaft 55 is coupled to the pivotal stem 45, and extends through a flexible housing 56, where its other end is coupled to the worm wheel 52, Fig. 2.

This worm wheel 52 is in mesh with the worm gear 53, which is keyed or otherwise secured to the shaft 54 extending through the hollow trunnion shaft 57. The outer end of this shaft 54 has secured thereto another worm gear 61. This gear is driven by the shaft 63 through the worm wheel 62. The shaft 63 is driven by the shaft 60 "take-off" gear 60, shaft 64, and worm 65. The teeth of this main "take-off" gear 60 mesh with the teeth of the ring gear 34 secured to the outer ring 30, so that as the turret is trained about its azimuthal axis the movement of the turret relative to this outer ring 30 and ring gear 34 is transmitted to the pivotal stem 45 and arm 41.

The number and size of the gears are selected so that the bead 40 is moved in a direction opposite to the gun's movement and through an equal angle, so that, as the turret is trained to one side

of the fore and aft axis of the aircraft the arm 41 which carries the bead 40 trails behind the train of the gun and turret by an equal angle and remains parallel to the line of flight, irrespective of the angle of train.

The entire body 50 of the adjustable bead structure is rotatable in the bore 39 of the bracket 37 so that as the turret and gun are moved in elevation about the trunnion shaft 57, the movement is transmitted to the adjustable bead. The spindle 52 carries at its outer end a beveled gear 66. This beveled gear 66 is in mesh with the beveled gear 67 which is secured to an end of the stub shaft 68. This shaft is rotatable in a bearing structure similar to that described in connection with the bearing support for the pivotal stem 45. The opposite end of this stub shaft is coupled to the flexible driveshaft 70 which extends through the flexible housing 71, where its other end is coupled to the worm wheel 72. This worm wheel meshes with the worm gear 73 which is keyed to the trunnion shaft 57, so that as the turret is elevated or depressed to aim the gun above or below the plane of the line of flight the bead 40 will be rotated in the perpendicular plane about the axis 6-6 and at an angle equal to the angle of elevation but in a reverse direction, so that the arm 41 of the bead 40 will remain parallel to the fore and aft axis of the aircraft, irrespective of the angle of elevation of the gun.

The two component motions above described are imparted to the bead independently or concurrently when the gun is moved laterally or in elevation or in some resultant of the two directions of movement. The distance between the axis 5-5 of the pivotal stem 45 and the plane of the ring sight, as shown in Fig. 1, is proportional to the muzzle velocity of the bullet, and the distance from the axis 5-5 to the center of the bead 40 is (with the same function of velocity) of a length proportional to the air speed. The path of the bullet is the resultant of the above components of motion and the line of sight should be parallel to or coincide with the path of the bullet for stationary targets at the ranges for which these sight are effective.

The important feature of my invention is that the arm which carries the bead is kept parallel to the fore and aft axis of the plane by keeping the axis 5-5 perpendicular to the roller path of the turret, and by training the arm about the axis 5-5 an amount equal to the angle of train of the turret on its roller path but in the opposite direction. In case the roller path of the turret is inclined to the fore and aft axis of the plane, it is only necessary to bend the arm 41 which carries the bead 40 through an angle equal to the angle of inclination of the roller path.

In Figs. 7, 8 and 9, I have shown diagrammatically the position of the gun relative to the axis of the aircraft and the position of the arm 41 for various positions of elevation and train of the gun. The rear sight is indicated at 38 and the forward bead sight at 40. The arrow A in each figure shows the direction of flight of the aircraft. In each figure the point C indicates the position of a stationary target, and OC is the line of sight. The line BD is in the direction of the axis of the bore of the gun and would be the normal sight line if the bead 40 were in the axis 5-5 of the pivotal stem. This line BD also represents the motion of the bullet, due to the explosion of the charge in the chamber of the gun. This would be the true path of the bullet were it not for the motion of the craft. The line OC

is the corrected sight line as determined by the ring and the bead. The path of the bullet is substantially parallel to this line. In each of these figures the line CD represents the component of the velocity of the bullet due to the motion of the aircraft.

It should be noted that in each of the figures the arm 41 is always parallel to the arrow A, indicating the fore and aft axis of the aircraft and the direction of its movement.

Obviously, the sight will function for altitudes higher than illustrated in Fig. 9. In fact, the operator may elevate the turret up to and beyond the vertical as well as below the horizontal.

The obstruction to the bead sight, as viewed from Fig. 2 is not so apparent in Figs. 7, 8 and 9, and in actual operation the limited position of elevation and of train, wherein the supporting structure of the movable arm would obstruct the gunner's view of the bead, does not affect the usefulness of this sight over the greater part of the hemisphere in which the gun may be pointed.

It is, therefore, apparent that I have devised a useful gun sight for a turret mount which properly and accurately corrects for "gunners deflection" for all angles of elevation and train. My particular gun sight is not, however, limited to use only with a turret mount. In Fig. 6 I have illustrated my gun sight as applied to a standard flexibly mounted machine gun. The gun 13 and the recoil guide and slide member 36 are secured to its supporting frame 80 by means of the forward and rear gun mount adapters 23 and 24. This assembly, comprising the gun, recoil guide and slide, mount adapters and supporting frame, is rotatably mounted on the trunnions 81 between the frame 80 and yoke 82. The yoke 82 is mounted for movement about a vertical axis of the pedestal support 83 by means of a stem and bearing structure, not shown. The front sight assembly is secured to the recoil guide and slide by means of the bracket 37, while the rear ring sight is mounted directly to the rear gun mount adapter 24.

The front sight assembly is identical to that illustrated in Figs. 4 and 5, and further description is unnecessary, except that in the mounting here illustrated the flexible driveshaft 55 in the flexible housing 56 is coupled to the gear 84. This gear is in mesh with the pinion 85, driven by the larger satellite gear 86 mounted on the opposite end of the pinion shaft. This reduction gearing assembly is shown as journaled in the supporting frame 81 which is secured to the yoke 82, so as to be rotatable therewith about the azimuthal axis of the pedestal mount as the gun is moved in train. The larger satellite gear 86 meshes with and is adapted to roll around the stationary non-rotatable gear 88, which is fastened to the stationary part of the pedestal supporting structure. As the gun is swung laterally the yoke 82 turns on its azimuthal axis, carrying with it the gear assembly including the satellite gear 86, which is rotated in its bearing surface driving the pinion 85 and the gear 84. The gear 84 is coupled to an end of the flexible shaft and drives the pivotal stem 45 of the adjustable bead 40. This causes the arm 41 carrying the bead 40 to swing about the axis 5-5 of the pivotal stem 45. The size of the gears are selected so that the arm of the bead will swing through an angle equal to the train of the gun relative to the fore and aft axis of the craft but in the reverse direction.

The gear 89 is secured to the trunnion 81 by

means of the screws 83' so that its axis is in alignment with the axis of the trunnion. The gear 90 is mounted on the frame 86 and as the gun is elevated, the gear 90 revolves about the stationary gear 89. The gear 90 drives the beveled gear 91 which is coupled to the flexible driveshaft 70 mounted on the flexible housing 71 and the beveled gear 67. The beveled gear 67 meshes with the beveled gear 66 which is secured to the spindle 52 of the body portion 50 of the bead supporting structure, so that as the gun is elevated or depressed, the arm 41 of the bead 40 and the body portion 50 will be rotated in a vertical plane about the axis 6-6 in order to keep the arm 41 parallel to the direction of flight or to keep the axis 5-5 of the body portion 50 or pivotal stem 45 perpendicular to azimuthal or lateral reference plane.

It should be pertinent to observe at this point the particular advantage of the adjusting mechanism which I have illustrated over the prior art, particularly illustrated by the patent to Inglis, referred to above. As previously suggested, the corrections introduced by the mechanism embodying my invention, which I claim to be novel, are correct for any and all angles of elevation and train.

In Figs. 10, 11 and 12, I have illustrated a modification of my sight adjusting mechanism. In this embodiment the adjusting mechanism is similar to that disclosed in Figs. 4 and 5, except that the vertical axis about which the bead is rotated is laterally offset from the supporting bracket, so that the supporting bracket will not interfere with the line of sight established by said bead and rear sight.

Fig. 10 illustrates the sight as viewed by the gunner. In this figure the arrow indicates the direction of flight of the plane and for the arm 112 of the bead 115 to take the position illustrated the gun would be trained 90° to the right of the fore and aft axis of the aircraft, or abreast the starboard beam. The arm 112 is affixed to and adapted for rotation with the spindle 100 so that the length of the arm may be adjusted by set screw, for example to correspond to the air speed of the firing plane. This spindle is supported in the angular bracket 101 in much the same manner that the pivotal stem 45 is supported in the body 50 as shown in Figs. 4 and 5. The flexible driveshaft 55, enclosed in the flexible housing 56 is coupled to this spindle as at 102.

The angular bracket 101 is supported by the main bracket 105 so as to be rotatable about the horizontal axis 6'-6'. The pin 103 is keyed to the angular bracket 101 at 103', and this pin is rotatably supported in a bore 106 formed in the main supporting bracket 105. The worm gear 104 is keyed to this pin so as to be rotated by the worm 116 secured to the end of the spindle 107. The spindle 107 is rotatable in a bearing formed in the main bracket 105 and held in position by means of the two collars 109 and 110. This spindle 107 is coupled to the flexible shaft 70, as indicated at 113.

Obviously, the flexible shafts 55 and 70 are each provided with a driving engagement, as illustrated in Figs. 1 to 3, or Fig. 6, so that as the turret or gun is moved in elevation or train relative to the fore and aft axis of the plane the movement is also transmitted to the angular bracket 101, or the spindle 100, so as to maintain the arm 41 parallel to the fore and aft axis of the aircraft and maintain the axis 5'-5' perpen-

dicular to the turret roller path or lateral reference plane.

The circular outline shown in Fig. 11 indicates the path of the center of the bead 115 as the bracket is rotated about its axis 6'-6', when the bead and arm are in a position 90° from that illustrated in Fig. 10. The circular outline shown in Fig. 12 indicates the path of the center of the bead as the arm 112 is rotated about the axis 5'-5'. The particular advantage of this modification over that disclosed in Figs. 4 and 5 is thus apparent, since as these circular outlines indicate, the supporting structure will not interfere with the line of sight at any position of the gun relative to the axis of the aircraft.

Other modifications and changes in the number and arrangement of parts may be made by those skilled in the art without departing from the nature of this invention, within the scope of what is hereinafter claimed.

The invention described herein may be manufactured and/or used by or for the Government of the United States of America for governmental purposes without the payment of any royalties thereon or therefor.

I claim:

In combination, a gun turret of the free gun type, a trunnion support therefor about which the turret is movable in elevation, a roller path having a stationary portion upon which the turret is movable in train, a compensating gun sight adapted to be mounted to a machine gun mounted in said turret, including a sighting element having a laterally offset arm, a rotatable spindle, means for securing said arm to said rotatable spindle with said sighting element laterally offset from the axis of rotation thereof, and with said arm parallel to the plane of the roller path, a flexible shaft secured to said spindle and having a driven engagement with the stationary portion of said roller path, whereby the movement of the gun in azimuth about said roller path will be transmitted to the spindle and arm, and means for maintaining the axis of rotation of said spindle perpendicular to the plane of the roller path as the turret is elevated about the axis of the trunnions, said last named means comprising a rotatable support for the assembly comprising said spindle, arm, and sighting element, whereby the assembly may be rotated about an axis normal to the axis of said spindle, and means for rotating said support and said assembly about said axis comprising a flexible shaft having a driving engagement with said trunnions whereby the assembly will be rotated as the turret is moved in elevation.
